UNITED STATES PATENT OFFICE.

MOSES L. FOOTE AND WILLIAM M. KINGSBURY, OF CLEVELAND, OHIO.

HOT-BLAST RADIATOR.

1,292,291.

Specification of Letters Patent. Patented Jan. 21, 1919.

Application filed March 5, 1918. Serial No. 220,562.

To all whom it may concern:

Be it known that we, MOSES L. FOOTE and WILLIAM M. KINGSBURY, citizens of the United States, residing at Cleveland, in the 5 county of Cuyahoga and State of Ohio, have invented certain new and useful Improvements in Hot-Blast Radiators, of which the following is a specification.

Our invention has relation to that class 10 of radiators which are used in heating air driven over same by mechanical force, and adapted for the reception of steam at high or low pressure or any other heat conducting fluids or liquids. The several improvements 15 hereinafter specified may, however, be employed advantageously in radiators of the class known as "in-direct" radiators, or those which are located in an air-conducting flue at a distance from the space to be heated.

An object of our present invention is, to 20 simplify the construction, reduce the cost of radiators by reducing the number of separate pieces and the number of joints to be 25 made up and we attain this object, among others, by means of the construction and arrangement of parts, and the ease of assembling of the devices hereinafter described, by which the fluids shall be suitably sub-di- 30 vided within the structure, causing a positive circulation and air expulsion through the loops, and exposing a large heating surface of metal to the air to be heated, and to so arrange and construct the sections that it 35 may be made of cast or other metal, being united by what is known as a slip-nipple joint secured together by means of bolts or screw joints for assembling and it can be readily united for use or dis-united for re- 40 pairs.

The heating surface of loops consists of a series of extended projections cored out, tapered and curved, which allows for expansion and eliminates any possible water de- 45 posits. There is no chance of retarding the air as the projections are spaced equally and formed so as to split the air, and the friction is reduced by the projections being so formed that three rows of projections are 50 splitters while two inner rows are circles de- signed to rap the air which makes impinge- 55 ment perfect and all sides effective. The resistance can be increased or decreased by a variation of the connections. These projec- tions or extended heating surface are set on an angle running horizontally.

The internal construction of each section is divided into three parts, the center chamber and two outer chambers. The center chamber receives the fluids or liquids at the 60 bottom thereof and conveys same to the top of the section for distribution to the outer chambers without coming in contact with the fluids or liquids of the outer chambers. By this method of construction we obtain a 65 drop or minus pressure on the outer chambers, which causes a partial vacuum to be formed thereby causing the air, steam or other liquids, to be drawn completely 70 through the entire section and to be expelled through the bottom orifice. There is also constructed at the bottom of the center chamber of each section a small drip hole for taking away any excess fluids and below this drip hole is constructed a seal for the 75 purpose of preventing pressure entering from outer or other chambers.

To accomplish all of this, our improvements involve certain novel and useful peculiarities of construction, relative arrangements, or combinations of parts and details of manufacture, all of which will be herein first fully described and then pointed out in the claims.

In the accompanying drawing, forming 85 part of this specification,

Figure 1 is a side elevation of a radiator section;

Fig. 2 is an end elevation of the radiator section;

Fig. 3 is a section thereof on the line B—B 90 of Fig. 2;

Fig. 4 is a section thereof on the line D—D of Fig. 3;

Fig. 5 is a section on the line F—F of 95 Fig. 3;

Fig. 6 is a top view.

The heater consists of a series of sections of the vertical type and as the sections are practically identical a description of one 100 will answer for all.

Each section consists of an outer wall or casing 6 with an internal U-shaped partition 7 extending lengthwise therein. The bend or lower end of this partition extends 105 around the inlet opening 8 for the steam or other heating medium, and the upper ends of this partition are spaced away from the top 9 of the section. Thereby a passage for circulation is formed leading upwardly from 110 the opening 8 between the walls of the part 7 and connecting at the top with the outer

passages 9 through which the steam flows downwardly to the bottom of the section which connects through openings 10 with the adjacent outlet sections of the radiator.

- 5 The top plates of the sections are extended as shown at 11, on the sides thereof, forming spacing projections which abut against each other when the sections are assembled side by side. This plate may be strengthened as 10 shown at 12. The lower ends of the sections are connected together, and also spaced apart, by the taper nipples 13 and 14 at the inlet and outlet bosses, respectively.

The side walls of each section are formed 15 with symmetrical rows of cored projections as shown, some of these projections being circular as indicated at 15 and some being somewhat oval shaped as indicated at 16, but with sharp edges 17 presented in a direction 20 parallel to the flow of air transversely of the sections, as is usual in force flow or hot blast systems of the kind referred to.

It will be noticed that the rows of projections provided with the sharp edges are 25 arranged in alternation with the rows of circular projections, as shown, the two outer and the middle rows being of the former type, and the rows of circular projections intervene. As the air flows across or 30 through a battery of these sections it will be divided by the outer row and will then pass around the projections of the next row which are respectively located in line with the openings between the projections of the 35 outer row. The effect of this is to equally distribute the air across the entire surface of the radiator, whereby it is uniformly and effectively heated.

The assembled sections are secured together by bolts 20 which engage in notches 21 formed at the outer edges of the sections. These bolts are placed adjacent to the nipple connections, so that the nipples may be drawn tight, and by removing the 45 bolts and separating the sections somewhat, any section can be removed and replaced, without loosening all the sections or joints of the battery.

In the lower part of each section there is 50 provided a curved wall or trap 22 extending across the section. This is spaced somewhat below the bend of the U-shaped partition 7, which is provided at its lowest point with a drain opening 23, and with two 55 pending flanges 24, which dip into the cup or

recess formed by the part 22, providing a water seal or trap which allows the escape of condensation and prevents the escape of steam.

The circulation of steam from its inlet at 60 8 is upwardly between the branches of the partitions 7 and over the top thereof, and downwardly through the passages 9 to the chamber at the bottom of the section, and thence out through the openings 10. 65

A radiator constructed of the sections described will have decided advantages with respect to heating efficiency.

We claim:

1. A radiator section having a U-shaped 70 partition therein forming a middle up-flow passage provided with an inlet at its lower end and outer down-flow passages communicating with said passage at its upper end and provided with a separate outlet spaced 75 below said inlet and partition.

2. A radiator section having a U-shaped partition therein forming a middle up-flow passage and outer down-flow passages communicating with said passage at its upper 80 end, and a condensation chamber below the said partition, the up-flow passage having an inlet at its lower end above the bottom of said partition, and the condensation chamber having an outlet below said partition. 85

3. A radiator section having a U-shaped partition therein, the bend of the partition being located toward the bottom of the section and the upper ends of the partition terminating short of the top of the section, said partition forming a middle up-flow passage and two lateral down-flow passages, the section having an inlet into the lower end of said middle passage and an outlet at 95 the bottom from said lateral passages. 90

4. A radiator section having a middle longitudinal up-flow passage, and outer longitudinal down-flow passages communicating at their upper ends with said middle passage, said middle passage having a trapped outlet at the bottom thereof, into the lower part of the section. 100

In testimony whereof we do affix our signatures in presence of two witnesses.

MOSES L. FOOTE.

WILLIAM M. KINGSBURY.
